UNITED STATES PATENT OFFICE.

ERASTUS E. WINKLEY AND FRED V. HART, OF LYNN, MASSACHUSETTS, ASSIGNEES, BY MESNE ASSIGNMENTS, TO WINKLEY ENGINEERING COMPANY, OF KITTERY, MAINE, A CORPORATION OF MAINE.

HYDROCARBON-MOTOR.

No. 909,728.

Specification of Letters Patent.

Patented Jan. 12, 1909.

Application filed April 2, 1903. Serial No. 150,705.

To all whom it may concern:

Be it known that we, ERASTUS E. WINKLEY and FRED V. HART, citizens of the United States, residing at Lynn, in the county of Essex and State of Massachusetts, have invented certain new and useful Improvements in Hydrocarbon-Motors; and we do hereby declare the following to be a full, clear, and exact description of the invention, such as will enable others skilled in the art to which it appertains to make and use the same.

The present invention relates to hydrocarbon-motors and more particularly to that class of motors which are adapted to be reversed in their direction of rotation while in continuous operation.

The object of the present invention is to produce a hydro-carbon motor which may be operated in either direction and which may be reversed in its direction of rotation without excessive shock or strain upon the motor, without danger of stalling, and without being brought to a complete standstill and then started in the reverse direction by hand or by complicated auxiliary mechanism.

With these objects in view the present invention consists in the devices and combination of devices hereinafter described and claimed.

Two-cycle motors as at present constructed are usually adapted for operation in either direction, but as they are not self-starting it is the common practice to operate them continuously in one direction and, where the driven shaft must be capable of rotation in both directions, to provide reversing gearing between the motor and the driven shaft, thus avoiding stopping the motor and then starting it by hand in the opposite direction. Four-cycle motors on the other hand are adapted to operate in but one direction, and with this type some form of reversing gearing is absolutely necessary.

According to our present invention we utilize a premature ignition during the compression stroke to set the motor in operation in the opposite direction. To avoid excessive shock and strain upon the motor, we first reduce the speed thereof, preferably by rendering the ignition device inoperative, and in order to avoid the possibility of stalling the motor we have provided means con-

trolled by the speed thereof which will render the mechanism operative to cause premature ignition only when the speed has reached such a point that a premature explosion which would be sufficient to stop the motor, would certainly start it in operation in the reverse direction. We have also provided mechanism whereby the times of operation of the exhaust valve and of the ignition device may be shifted for reverse rotation.

In the accompanying drawings we have shown our invention as embodied in a single-cylinder, vertical, four-cycle, hydro-carbon motor with suction-operated inlet valve and make and break ignition device. Moreover, we have shown automatic mechanism arranged to actuate the ignition device abnormally early during the compression stroke and only when the speed of the motor has fallen so low that a single explosion will stop and then start the motor in the opposite direction. We have also shown automatic means for shifting the times of operation of the exhaust valve and of the ignition device for reverse rotation of the motor. Our invention, however, is not limited to the construction described and shown as in its broader aspects it contemplates a hydro-carbon motor having a cylinder, a piston, a shaft, an ignition device, and speed controlled means combined with auxiliary mechanism whether automatic or not for actuating the ignition device during a compression stroke to reverse the direction of rotation of the shaft.

In addition to the advantages heretofore enumerated our improved motor possesses many other advantages which will be apparent to those skilled in the art, and our invention is not limited to a motor in which each and every one of these advantages are present as a motor possessing only a portion of these many advantages would be within the spirit of the present invention.

In the accompanying drawings which disclose a preferred form of our invention Figure 1 is a front elevation of a hydro-carbon motor provided with our improved reversing mechanism, the fly wheel being removed; Fig. 2 is a side elevation looking toward the right in Fig. 1, while Fig. 3 is a corresponding side elevation looking toward the left in Fig. 1; Fig. 4 is an enlarged front elevation of the reversing mech-

105
110

anism with the sprocket chain and speed controlled device removed; Fig. 5 is a horizontal section on line 5—5 Fig. 4; Fig. 6 is an enlarged side elevation of the reversing mechanism looking toward the right in Fig. 4 except that the parts are in the positions they occupy after the direction of rotation has been reversed; Fig. 7 is a corresponding elevation but from the opposite side; Fig. 8 is a detail showing the hand-actuated sleeve and the shipping lever in position to cause shifting of the ignition and valve actuating devices for reverse rotation; Fig. 9 is a detail showing the bracket which carries the studs upon which are mounted the shipping lever and one of the levers of the auxiliary mechanism for actuating the ignition device; Fig. 10 is a side elevation and Fig. 11 a top plan of the shipping lever and parts carried thereby, Fig. 12 is a detail of the lever which directly engages and actuates the ignition device, while Fig. 13 is a vertical section of the ignition device.

Mounted to reciprocate within the cylinder 1 (see Fig. 3) is the piston 2 connected by means of the rod 3 with the crank 4 formed in the main shaft 5 which is mounted in bearings 6—6. A fly wheel 7 is provided as is usual with these motors. The explosive mixture is led from a suitable carbureter (not shown) through the inlet pipe 8 to the suction-operated inlet valve 9 of the ordinary spring-controlled type, while the exhaust gases escape through the exhaust pipe 10 controlled by the positively opened exhaust valve 11. The cooling water is conducted to and away from the cylinder through the inlet pipe 12 and outlet 13 respectively.

The ignition device is of the ordinary make-and-break type and comprises a fixed and a movable electrode 131 and 132. The fixed electrode 131 mounted upon, but insulated from, the support or plate 14 is connected with the wire 15 leading to one pole of a battery (not shown) or other source of electricity, the wire 16 leading from the other pole of the battery being attached directly to the plate 14, a suitable spark coil (not shown) being inserted in the electric circuit. The movable electrode 132 is fixed upon the inner end of a shaft 17 which is mounted to oscillate in a bearing in the plate 14, its outer end carrying fixed thereon the depending arm 18 having the horizontal portion 19. A spring 20 fixed in the post 21 bears against the arm 18 and tends to oscillate the shaft 17 to swing the movable electrode into contact with the fixed electrode within the cylinder.

The ignition device is operated normally by the following mechanism:—Fixed upon the main shaft 5 is the gear 22 meshing with the gear 23 pinned upon the hub 24 of the sprocket wheel 25 which is free to rotate

upon the stud 26 secured in the support 27 by means of the set screw 28. Rotatably mounted upon the stud 29 projecting from the plate or base 30 secured upon the wall of the cylinder by means of the screws 31 is the sprocket wheel 32 having the same number of teeth as sprocket 25. A sprocket chain 33 connects the sprocket wheels and positively drives sprocket 32 at one-half the speed of the main shaft 5, gear 23 being just twice the diameter of gear 22. Upon the elongated hub of sprocket 32 are fixed the two cam disks 34 and 35 for the ignition and the exhaust valve actuating devices respectively. Each of these disks carries two cams, one for forward rotation and the other for reverse rotation, and by means of suitable devices one cam is automatically rendered operative and the other inoperative when the direction of rotation of the motor is reversed. The ignition device is actuated during the normal operation of the motor in one direction or the other by means of the actuating lever 36 pivoted upon the stud 37 and carrying at one end the projection 38 arranged through mechanism hereinafter to be described to engage either the forward cam 39 or the reverse cam 40 upon the disk 34 according to the direction of rotation of the motor. The upper end of the lever 36 is recessed at 41 and engages the horizontal portion 19 of the arm 18 fixed upon the electrode-carrying shaft 17, while the spring 42 acts normally to hold the projection 38 against the face of the cam disk 34.

As it is often desirable to vary the point of ignition we have provided means whereby the ignition may be effected at an earlier or a later point in the cycle of operation, and this is accomplished by raising or lowering the pivotal support of lever 36 in the following manner:—Pivotaly mounted upon the stud 43 is the lever 44 carrying at one end the stud 37 upon which the actuating lever 36 for the ignition device is supported. The other end of the lever 44 carries the handle 45 by means of which the lever may be conveniently swung about its pivotal support 43 to raise or lower the stud 37 and thus cause an earlier or a later engagement of the projection 38 with the cams 39 or 40. In order to limit the movement of lever 44 in each direction, and in order to hold it in its adjusted position, we have provided the segmental plate 46 having the abutments or stops 47 arranged to engage the finger 48 projecting from the lever (see Fig. 11) and to limit the movement of the same. The lever is held in its adjusted position by means of the spring-pressed detent 49 which is arranged to enter the recesses or depressions 491 in the plate 46 and to prevent accidental movement of the lever. The end of the detent is conical so that but little force is required to cause the detent to ride 130

up out of the depression and to allow the lever to be swung into a different position.

The means for actuating the exhaust valve consist briefly of a pivoted lever, one end of which is arranged to depress the valve spindle as the other end is raised through suitable connections by one or the other of the cams upon the cam disk 35. Pivotally supported upon the bracket 50 on the head of the cylinder of the motor is the lever 51, one end of which 52 is bifurcated to straddle the spindle of the exhaust valve 11 upon which are mounted the collars 53 and 54, the one above and the other below the bifurcated end 52, the spring 55 normally holding the valve raised or closed. Upon the stud 43 is pivoted the lever 56 carrying a cam roll 57 which is arranged by means hereinafter described to engage the cam 58 or 59 according to the direction of rotation of the motor. The rod 591 provided with the spherical ends is seated in corresponding recesses in the levers 56 and 51 and oscillates the latter lever to open the exhaust valve as the cam roll 57 is raised by one or the other of cams 58 and 59.

Having thus described the means for normally operating the motor in one direction or the other, we will now describe the manner in which the mechanism for actuating the exhaust valve and the ignition device is shifted from one set of cams to the other when the direction of rotation of the motor is reversed. Slidingly mounted upon the stud 60 projecting from the base or support 30 is the sleeve 61 (see Fig. 10) which is held from rotation upon its support by means of the depending arm 62 provided with the forked end 63 which straddles the pin 64. The segmental plate 46 is formed integral with the sleeve 61 and carries fixed therein the stud 43 upon which the levers 44 and 56 are pivoted (see Fig. 11). The stud 60 is sufficiently long so that the sleeve 61 may be moved longitudinally thereon to bring the cam roll 57 on lever 56 and the projection 38 on lever 36 into contact with either one of the two sets of cams on cam disks 35 and 34 respectively so that the exhaust valve and the ignition device will be operated at the proper times for forward or for reverse rotation of the motor.

The sleeve 61 is shifted upon its support 60 by means of a spring-actuated shifting-lever which is rendered operative by speed controlled mechanism. This shifting-lever 65 is pivoted upon the stud 66 projecting from the arm or bracket 67 which is formed integral with the base or support 30 (see Fig. 9). The upper end of lever 65 is formed with a cylindrical head 68 which engages upon each side the stops or abutments 69 upon the sleeve 61. Springs 70 and 71 for actuating the shifting lever are secured to the same by means of the screws 72 and are arranged to

be compressed as shown in Fig. 8 by the projections 73 upon the sleeve 74 which is adapted to be moved longitudinally upon its supporting stud 75. This sleeve is held in its adjusted position by means of a pin 76 in the stud 75 which passes through the U-shaped slot 77 on the sleeve (see Fig. 5). The handle 78 is provided by means of which the sleeve may conveniently be rotated upon its support 75 to bring the pin into the longitudinal portion of the slot 77 when the sleeve may be shifted longitudinally and then locked in its adjusted position by depressing the handle and causing the pin to travel along the transverse portion of the slot.

In order to prevent the immediate shifting of the lever 65 under the action of spring 71, we have provided means which are arranged to engage the lower end of the shifting lever and to prevent its turning upon its pivotal support until the proper time. Pivoted upon the stud 79 fixed in the base or support 30 is the sleeve 80 from which project the two arms 81 and 82. The lower end 83 of the shifting lever 65 is offset as shown in Fig. 4 and is arranged to be engaged by the end of arm 81 upon one side or the other as shown in Fig. 5 according to whether the sleeve 74 has been moved to put spring 71 or spring 70 under compression. If now the arm 81 be raised to clear the end 83 of the shifting lever 65, the spring under compression will immediately swing the lever upon its pivotal support and ship the sleeve 61 and parts carried thereby from forward to reverse position or vice versa.

The arm 81 is raised by means of the coiled spring 84 attached at one end to the arm 85 depending from the sleeve 80 and at the other end to the lever 86, pivoted upon the stud 87 and provided at its upper end with the horizontal portion 88 arranged to latch over the upper end of arm 82 as shown in Fig. 5 and to hold both of the arms 81 and 82 depressed against the tension of the spring 84. This horizontal end 88 of the lever 86 carries the pin 89 for a purpose hereinafter to be described. The lower end of this lever is provided with a rounded projection 90 which, when the end 88 is latched over the end of arm 82 will be in position to be engaged under certain conditions by the cam 91 held from rotation upon, but movable longitudinally along, the sleeve or hub 92 of the sprocket wheel 93 which is rotatably mounted upon the stud 94 projecting from the lower end of the base or support 30. This cam is so formed and timed that one of the inclined faces thereof may actuate lever 86 at the proper point in the compression stroke in whichever direction the motor may be running, although it is arranged to be held normally out of the plane of the lower end of the lever 86 so that it will not be in position to strike the projection 90 even

when the latter is depressed by the latching of the upper end of the lever 86 over the arm 82, and this is accomplished by means of mechanism controlled by the speed of the 5 motor which, when the predetermined speed is exceeded, will hold the cam at some point intermediate the sprocket wheel 93 and the projection 90. This mechanism consists, as shown in Figs. 2 and 3, of the rotating head 10 or carrier 95 upon which are pivoted the weighted arms 96 the inner ends of which are arranged to engage projections 97 upon the sleeve 98 carrying the cam 91. The head 95 is fixed upon the sleeve 92 of the sprocket 93 15 which is located between the sprockets 25 and 32 and is driven by the chain 33. The spring 99 engaging at one end the shoulder 100 on the sprocket 93 and at the other the disk of cam 91 acts normally to move said 20 cam away from sprocket 93 and into position to strike the projection 90 of lever 86. During the normal operation of the motor, however, the weighted arms 96 swing upon their pivots and their inner ends engage the projections 25 upon the sleeve 98 and move it and the cam 91 toward the sprocket 93 against the action of spring 99, thus holding the cam in inoperative position. After the ignition device has been rendered inoperative and as 30 the speed of the motor diminishes, the centrifugal action also diminishes and the spring 99 will gradually move the cam away from sprocket 93 until finally, when the predetermined speed is reached, the cam will be in 35 position to strike the projection 90 of lever 86 when the parts are in the position shown in Fig. 4 and will release arms 82 and 81, permitting the shipping lever 65 to oscillate to shift the ignition and exhaust valve actuating mechanism from one set of cams to the other.

In order to provide for conveniently resetting the devices so that they may be in position to shift the levers from one set of 45 cams to the other, we have provided a curved finger 101 projecting from the sleeve 74 and a horizontal pin 102 projecting from the end of arm 82. The finger 101 is arranged to be engaged by the pin 102 when 50 the arm 82 is released from lever 86, thus preventing the arm from rising so far that the horizontal end 88 of lever 86 can slip under the end of the arm 82, and when in resetting the devices the handle 78 is raised 55 to the position shown in dotted lines in Fig. 4 to bring the pin 76 into the longitudinal portion of the slot 77, this curved finger 101 will depress the pin 102 and with it the arms 82 and 81 so that the end 88 of lever 86 will 60 latch over the end of arm 82, holding both arms in their lowermost position and before sleeve 74 is shifted longitudinally to put spring 70 or 71 under compression.

We will now describe the essential feature 65 of our invention, namely, the mechanism

which is combined with speed controlled means to actuate the ignition device to reverse the direction of rotation of the motor. Pivoted upon the stud 103 fixed in the bracket 67 is the lever 104, the lower end of 70 which is adapted to engage the pin 89 in the end 88 of lever 86, while the upper end is recessed at 105 to receive the pin 106 on the lower end of the ignition actuating lever 36. During the normal operation of the motor 75 this lever 104 will be in the position shown in Fig. 1, permitting the lever 36 to be actuated by one or the other of the cams 39 and 40. When, however, it is desired to reverse the motor and the end 88 of lever 86 80 is latched over the end of arm 82, the pin 89 will swing the lower end of lever 104 to the left, as shown in Fig. 4, carrying the upper end to the right and moving the lower end of lever 36 in the same direction so that 85 the projection 38 will not be engaged by one or the other of the ignition cams. The ignition device is thus rendered inoperative, the electrodes being held in contact, but when the speed falls to the predetermined 90 speed, the speed controlled mechanism moves cam 91 into position to strike the depressed end of lever 86 and to oscillate said lever, swinging the pin 89 to the right. In the motor shown in the drawings cam 91 is so 95 timed that the high part of cam 39 is at this time beneath the projection 38 so that the electrodes will not be separated until sleeve 61 and parts carried thereby are shipped, when projection 38 will drop off the side of 100 cam 39 and the charge will be ignited.

The operation of our improved motor is as follows:—The motor having been started in forward rotation by hand or in any other suitable manner, the parts will occupy the 105 positions shown in Fig. 1, the ignition device being actuated by lever 36 and cam 39 and the exhaust valve by lever 51 actuated through suitable connections by cam 58. Arms 81 and 82 on the sleeve 80 are in their raised position, the end of arm 82 engaging the upper end 88 of lever 86 and holding the lower end 90 of said lever above the surface of cam 91 so that no matter what the speed of the motor may be the lever will not 110 be engaged by the cam. The shipping lever will be in the position shown in Figs. 2 and 3 with springs 70 or 71 under slight and substantially equal compression. When it is desired to reverse the motor all that is 115 required is to raise the handle 78, move it towards the motor and then depress it. The parts will then be in the position shown in Figs. 4, 5 and 8, arms 81 and 82 being held in their lowermost position by lever 86 which 120 has now been swung by the spring 84 so that its end 90 will be struck by cam 91 as soon as the latter has been moved into proper position by spring 99 upon the sleeve 92. Until this happens, however, lever 104 will 125

be held in its inclined position by the pin 89 on the end of lever 86, the upper end of lever 104 carrying the projection 38 on lever 36 out of engagement with ignition cam 39 and permitting spring 20 to oscillate the shaft 17 to swing the movable electrode 132 into contact with the fixed electrode 131. The speed of the motor will rapidly fall owing to non-ignition of the charges drawn into the cylinder and compressed, expanded, and then exhausted therefrom. When the motor reaches the predetermined speed, cam 91 will have been moved into proper position and will strike the end 90 of lever 86 and unlatch the upper end 88 from arm 82. The lower end of lever 104 being now free to swing to the right, it will permit projection 38 to engage the high part of cam 39, and the electrodes will be separated to form a spark within the cylinder the instant projection 38 drops off the side of cam 39 when the sleeve 61 is shipped. This follows close upon the releasing of lever 104 for as soon as the end 88 of lever 86 is swung clear of the top of arm 82 the latter arm will rise as will arm 81 the end of which clears the offset end 83 of the shipping lever 65 and permits the latter under the influence of spring 71 to be oscillated upon its support 66, moving the sleeve 61 and parts carried thereby into the positions shown in Figs. 6, 7, 10, and 11, so that cam roll 57 is in position to engage cam 59 while the projection 38 on lever 36 will engage cam 40, thus shifting the times of operation of the exhaust valve and of the ignition device to meet the new conditions of reverse rotation and establishing the complete cycle of operation.

Although in the specification and drawings we have shown our invention as embodied in a four-cycle hydro-carbon motor, it is equally applicable to motors having a different cycle of operation. Moreover, any suitable form of ignition device may be employed as our invention in its broader aspects is not limited to the particular type disclosed. Nor is it limited to a construction in which the speed of the motor is reduced by rendering the ignition device inoperative as the speed may be diminished in any other suitable or convenient manner. Moreover, although we have described and shown the reversing mechanism as constructed and arranged to reverse the motor by a single premature explosion, we do not limit ourselves to such a construction, as it is within the spirit of our invention to cause one or more retarding explosions before the reversing explosion, speed-controlled mechanism being combined with the actuating mechanism for the ignition device so that the first explosion shall occur at such a speed that when the last takes place reversal follows without fail. Furthermore, our invention is not re-

stricted to automatic mechanism for actuating the ignition device when the speed of the motor reaches the predetermined speed, except where so specified in the claims, as our invention in its broader aspects contemplates a construction in which the ignition device may be operated by hand but only after the speed of the motor has reached the predetermined speed. Nor do we limit ourselves to a construction in which the times of operation of the ignition device and of the exhaust valve are automatically shifted, as it is within the spirit of our invention to construct a motor in which this shifting is produced manually immediately at or about the time of the reversing explosion.

Having thus described our invention and its mode of operation what we claim and desire to secure by Letters Patent is:—

1. A hydro-carbon motor, having a cylinder, a piston, a shaft, an ignition device, means for actuating said device for forward and reverse rotation of the motor, mechanism for shifting the time of operation of said means for reverse rotation of the motor, and speed controlled means for rendering said mechanism operative, substantially as described.

2. A hydro-carbon motor, having a cylinder, a piston, a shaft, an ignition device, means for actuating said device for forward and reverse rotation of the motor, and speed controlled means for actuating the ignition device during a compression stroke to reverse the direction of rotation of the motor and for shifting the time of operation of said device for reverse rotation, substantially as described.

3. A hydro-carbon motor, having a cylinder, a piston, a shaft, an ignition device, means for normally actuating the ignition device, and auxiliary mechanism controlled by the speed of the motor for actuating the ignition device during a compression stroke to reverse the direction of rotation of the motor, substantially as described.

4. A hydro-carbon motor, having a cylinder, a piston, a shaft, an ignition device, means for normally actuating the ignition device, and automatic auxiliary mechanism controlled by the speed of the motor for actuating the ignition device during a compression stroke to reverse the direction of rotation of the motor, substantially as described.

5. A hydro-carbon motor, having a cylinder, a piston, a shaft, an ignition device, means for normally actuating the ignition device and auxiliary mechanism for actuating the ignition device during a compression stroke to reverse the direction of rotation of the motor, substantially as described.

6. A hydro-carbon motor, having a cylinder, a piston, a shaft, an ignition device, means for normally actuating the ignition

device and automatic auxiliary mechanism for actuating the ignition device during a compression stroke to reverse the direction of rotation of the motor, substantially as described.

7. A hydro-carbon motor, having a cylinder, a piston, a shaft, an ignition device, means for actuating said device for rotation of the motor in both directions, and spring-
10 actuated mechanism for shifting the time of operation of the ignition device for reverse rotation of the motor, substantially as described.

8. A hydro-carbon motor, having a cylinder, a piston, a shaft, an ignition device, means for actuating said device, spring-
15 actuated mechanism for shifting the time of operation of the ignition device for reverse rotation of the motor, a detent for said mechanism, and means for releasing the detent, substantially as described.

9. A hydro-carbon motor having a cylinder, a piston, a shaft, an ignition device, means for normally actuating the ignition
25 device during the forward and reverse rotation of the motor, and a speed-controlled auxiliary cam for controlling the actuation of the ignition device during a compression stroke to reverse the direction of rotation of
30 the motor.

10. A hydro-carbon motor having a cylinder, a piston, a shaft, an ignition device, means for normally actuating the ignition device during the forward and reverse rotation
35 of the motor, a detent and speed-controlled means for releasing the detent during the compression stroke to cause the actuation of the ignition device, whereby the direction of rotation of the motor is reversed.

40 11. A hydro-carbon motor, having a cylinder, a piston, a shaft, an ignition device, means for normally actuating the same for forward and reverse rotation, and speed controlled auxiliary mechanism for shifting the time of operation of said means and for actuating the ignition device, substantially as described.

50 12. A hydro-carbon motor, having a cylinder, a piston, a shaft, an ignition device comprising two electrodes arranged to be brought into contact and then to be separated at the proper time to ignite the charge in the cylinder, and means for maintaining the electrodes in contact at the proper time to render the ignition device inoperative to ignite the charge, substantially as described.

55 13. A hydro-carbon motor, having a cylinder, a piston, a shaft, an ignition device comprising two electrodes arranged to be thrown into and out of contact, a lever for actuating said device, a cam, means for holding the lever out of engagement with the cam to maintain the electrodes in contact to render the ignition device inoperative, and mechanism for releasing the lever

to render the ignition device operative, substantially as described.

14. A hydro-carbon motor, having a cylinder, a piston, a shaft, a valve, means for actuating the valve for forward and reverse rotation of the motor, mechanism for shifting the time of operation of said means for reverse rotation of the motor, and speed controlled means for rendering said mechanism operative, substantially as described. 70

15. A hydro-carbon motor, having a cylinder, a piston, a shaft, an ignition device, a valve, means for actuating said device and said valve for forward and reverse rotation, mechanism for shifting the times 80 of operation of said means for reverse rotation of the motor, and speed controlled means for rendering said mechanism operative, substantially as described.

16. A hydro-carbon motor, having a cylinder, a piston, a shaft, a valve, means for actuating the valve for forward and reverse rotation, and speed controlled means for shifting the time of operation of the valve for reverse rotation of the motor, substantially as described. 90

17. A hydro-carbon motor, having a cylinder, a piston, a shaft, an ignition device, a valve, means for actuating said device and said valve for forward and reverse rotation of the motor, and speed controlled means for shifting the times of operation of the said means for reverse rotation of the motor, substantially as described. 95

18. A hydro-carbon motor, having a cylinder, a piston, a shaft, an ignition device, a valve, means for reducing the speed of the motor, and mechanism operating automatically when the speed of the motor falls to the predetermined speed to actuate the ignition device during a compression stroke to reverse the direction of rotation of the motor and to shift the times of operation of the ignition device and the valve for reverse rotation, substantially as described. 100

19. A hydro-carbon motor, having a cylinder, a piston, a shaft, an ignition device, a valve, means for rendering the ignition device inoperative to reduce the speed of the motor, and speed controlled mechanism for actuating the ignition device during a compression stroke to reverse the direction of rotation of the motor and for shifting the times of operation of the ignition device and the valve for reverse rotation of the motor, substantially as described. 110

20. A hydro-carbon motor, having a cylinder, a piston, a shaft, an ignition device, an exhaust valve, forward and reverse cams for actuating said device and said valve for forward and for reverse rotation of the motor, a cam lever for actuating the ignition device, a cam lever for actuating the exhaust valve, common supporting means for said levers, and mechanism for moving said means 125

to shift the cam levers from one set of cams to the other, substantially as described.

21. A hydro-carbon motor, having a cylinder, a piston, a shaft, a valve, means for actuating the valve, and spring-actuated mechanism for shifting the time of operation of the valve for reverse rotation of the motor, substantially as described.

22. A hydro-carbon motor, having a cylinder, a piston, a shaft, a valve, means for actuating the valve, spring-actuated mechanism for shifting the time of operation of the valve for reverse rotation of the motor, a detent for said mechanism, and means for releasing the detent, substantially as described.

23. A hydro-carbon motor, having a cylinder, a piston, a shaft, an ignition device, means for actuating the ignition device, a valve, means for actuating the valve, automatic mechanism for actuating the ignition device to reverse the direction of rotation of the motor and for shifting the times of operation of said device and of said valve for reverse rotation, and a single hand-actuated device for rendering said mechanism operative, substantially as described.

24. A hydro-carbon motor, having a cylinder, a piston, a shaft, an ignition device, a valve, a shipping member for shifting the times of operation of the ignition device and the valve for reverse rotation, a spring for actuating said member, a detent for the shipping member, a single hand-actuated device for moving the detent into operative posi-

tion and for compressing the spring, and mechanism for releasing the detent, substantially as described.

25. A hydro-carbon motor, having a cylinder, a piston, a shaft, an ignition device, a valve, a spring-actuated shipping device for shifting the times of operation of the ignition device and of the valve, a detent for the shipping device, an ignition lever for rendering the ignition device inoperative, a latch lever for actuating the ignition lever and for holding said lever and the detent in their respective operative positions, hand-actuated means for moving the detent into operative position to permit the latch lever to actuate the ignition lever, and mechanism for operating the latch lever to release the detent, substantially as described.

26. A hydro-carbon motor having a cylinder, a piston, a shaft, means for normally producing power impulses in the cylinder during the normal operation of the motor in forward and reverse direction, and auxiliary mechanism controlled by the speed of the motor for producing a power impulse during the compression stroke of the piston to reverse the direction of actuation of the motor.

In testimony whereof we affix our signatures, in presence of two witnesses.

ERASTUS E. WINKLEY.
